UNITED STATES PATENT OFFICE.

WILLIAM H. HAWKINS, OF ALBANY, NEW YORK, ASSIGNOR OF ONE-HALF
TO JOSEPH WALTER, OF SAME PLACE.

FIRE-ESCAPE LADDER.

SPECIFICATION forming part of Letters Patent No. 259,537, dated June 13, 1882.

Application filed March 9, 1882. (No model.)

To all whom it may concern:

Be it known that I, WILLIAM H. HAWKINS, a citizen of the United States, residing at Albany, in the county of Albany and State of New York, have invented a new and useful 5 Fire-Escape Ladder, of which the following is a specification.

My invention relates to improvements in fire-escape ladders which are intended to be fastened to a building upon the breaking out 10 of a fire therein, for use during its continuance; and the objects of my improvements are, first, to afford a safe and ready means of escape for the occupants of the upper floors 15 of a building to the floors beneath, and for all persons occupying floors above the first story to make their escape to the ground safely and quickly; second, to enable the occupants of the lower floors to provide a safe and ready 20 means of escape for those occupying floors above them, and to use the same means whereby to effect their own escape; third, to enable firemen and others to quickly ascend the outer walls of lofty buildings, especially from story 25 to story, with greater rapidity and safety than is possible by means of ladders heretofore in common use. I attain these objects by the mechanism illustrated in the accompanying drawings, in which—

30 Figure 1 is a view in perspective of the entire ladder; Fig. 2, a vertical section of the entire ladder as it appears when fastened to a building in an elevated position; Fig. 3, a vertical section of a part of the ladder as it appears when fastened to a building in a suspended position; Fig. 4, a view in perspective 35 of the adjustable plate attached to the side pieces of the ladder; Fig. 5, a view in perspective of a building upon which ladders are elevated and suspended from story to story.

Similar letters refer to similar parts throughout the several views.

My invention consists of the ladder A, made of iron or other suitable material, similar in 45 construction to ladders in common use aside from the slots a a, extending through and along its side pieces from a point near the center to a point near the end n n of each of said side pieces. Then by means of the bolts b b, extending into and through the slots a a, and

made fast in the adjustable plate d, at or near its ends, I fasten said plate to the side pieces of the ladder A, upon which it is free to slide up and down from end to end of the slots a a. (See Fig. 1.) I do not, however, confine myself to this particular means of attaching the adjustable plate d to the side pieces of the ladder A, as it may be attached thereto in other ways fully as simple and effective. The hole at m' through the center of the adjustable 55 plate d, as shown in Fig. 4, then receives the bolt e, said bolt being of sufficient length to reach from the exterior surface beyond the interior surface of the walls of the building to which the ladder A is to be attached through 60 the opening W therein provided for a window, the bolt e also extending into and through the slots F F of the adjustable clamping-bars g h, which are retained upon the bolt e by means of the hand-wheel i, which is screwed upon 70 the thread-cut end of the bolt e, and freely adjustable thereon. (See Figs. 1 and 2.)

To elevate the ladder A upon the outside of a building from one story to another, I first slide the adjustable plate d, with the clamping-bars g h attached thereto, as hereinbefore described, up to or near the center of the ladder. I then raise the ladder upward through the window W, and as it is being brought back to a perpendicular position, its ends n n resting 80 upon and against the outer edge of the window-sill s, I adjust the clamping-bars g h across the inside of the window W, so that their ends bear against the inner surface, m, of the wall of the building, to which they are 85 then made fast by screwing the hand-wheel i up firmly against the bar n, which is back of and against the bar g, the ends n n of the ladder A being, by the last-named operation, firmly fastened against and upon the window-sill s, 90 the top of the ladder at the same time being thereby drawn back against the window-sill t of the story above, in which position the ladder A is securely held. (See Figs. 2 and 5.) The clamping-bars g h necessarily extending 95 across the window W, so that their ends may rest upon the inner surface, m, of the wall, upon both sides of the window W, as shown in Fig. 2, their adjustment is readily effected to any required position by means of the elong- 100

gated slots F F. (See Fig. 1.) One of the clamping-bars *g h* would be sufficient for the purpose to which the two are applied, as aforesaid; but both are permanently retained upon 5 the bolt *e* for the complete utility of my invention, as hereinafter appears.

To suspend the ladder *A* from the outside of a building from one story to another, I first slide the adjustable plate *d*, with the clamping-bars *g h* attached thereto, as hereinbefore described, down to the ends *n n* of the ladder, which is then lowered from the window *W* until the edge of the adjustable plate *d* rests upon the top of the window-sill *s*, at or near 10 its outer edge, the ends *n n* of the ladder *A* projecting perpendicularly above the window-sill *s*. I then adjust the clamping-bar *g* against the outer surface, *o*, of the wall of the building, upon the top of the window-sill 15 *s*, directly back of and parallel with the plate *d*, the ends of the bar *g* projecting beyond the ends of the plate *d* and beyond the side edges of the window *W*. I then adjust the clamping-bar *h* against the inner surface, *m*, of the wall 20 of the building, on a line parallel with the bar *g*. I then screw the hand-wheel *i* firmly against the bar *h*, thereby drawing the ends *n n* of the ladder *A* back firmly against the building, to which it is securely fastened by means of the 25 clamping-bars *g h*, being by the last-named operation firmly fastened to the wall of the building in their relative positions, as above described. (See Figs. 3 and 5.)

With one of my improved fire-escape ladders 30 conveniently at hand on each floor, the occupants of the highest buildings, from the uppermost stories down, can quickly provide for themselves a continuous fire-escape to the ground by suspending a ladder from each story, 35 one under another; or the ladders may be raised from story to story equally well and promptly by the occupants of the building, all as shown in Fig. 5. With two of these ladders, say, upon the fifth floor of a six-story building, one 40 of them may be raised to the sixth story, the other lowered to the fourth, and from the same window, if desired, as shown in Fig. 5, thereby enabling the occupants of the sixth and fifth stories to descend to the fourth, whereupon, by 45 removing the ladder elevated from the fifth story, descending the ladder suspended from the fifth story with it in hand, and suspending it from the fourth story, the occupants of the 50 sixth, fifth, and fourth stories will, by means 55 of the two ladders, have been provided with a

means of escape down to the third; or, where a ladder is elevated from the fourth and one from the fifth story of a six-story building, as shown in Figs. 2 and 5, the occupants of the sixth and fifth stories may descend to the fourth. 6c Then by removing the ladder elevated from the fifth story, descending the ladder elevated from the fourth story with it in hand, and suspending it from the fourth story, then by removing the ladder elevated from the fourth story, descending the ladder suspended as aforesaid from the fourth story with it in hand, and suspending it from the third story, as shown in Figs. 3 and 5, the occupants of the four upper stories will, by means of the two ladders, have 70 been provided with a means of escape down to the second story. This feature of my invention I consider of great importance, since, in memorable fires of recent date especially, the inability of firemen to rescue persons imprisoned 75 in the top stories of lofty buildings by means of ladders at their command demands that the occupants of the upper stories especially of a building shall have at their own command suitable means of effecting their escape down to a 80 story of a building at which outside aid can be made available in their behalf, or, better still, from the top of a building to the ground independently of such assistance.

As above described, my invention, simple in 85 construction, of enduring strength and ready adjustment upon the walls of a building, is adapted to a wider range of use than any fire-escape heretofore introduced.

What I claim as my invention, and desire to 90 secure by Letters Patent, is—

1. The combination, with a fire-escape ladder, of the vertically-adjustable plate *d*, carrying the bolt *e*, adjustable clamping-bars *g h*, and adjustable hand-wheel *i*, all substantially 95 as set forth.

2. The combination, in a fire-escape ladder, of one or more adjustable clamping-bars, *g h*, substantially as shown, for the purpose specified.

3. As a new article of manufacture, the reversible fire-escape ladder *A*, constructed and combined with means for securing it to the side of the building, substantially as shown, for the purpose specified.

WILLIAM H. HAWKINS.
